(57) **CLAIM**

The ornamental design for a film applicator as shown and described.

DESCRIPTION

FIG. 1 is a top, front, right side perspective view of the film applicator according to a first embodiment of my new design, showing a first configuration of the film applicator in an open state;

FIG. 2 is a bottom, rear, left side perspective view thereof; FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a rear, top, left side perspective view of the film applicator of the first embodiment, showing a second configuration of the film applicator in a closed state; and, FIG. 10 is a front, top, right side perspective view of the film applicator of the first embodiment, showing a second configuration of the film applicator in a closed state;

FIG. 11 is a first perspective view of the first embodiment of the film applicator coupled with an environmental showing of a mounting part for a film applicator;

FIG. 12 is a second perspective view of the first embodiment of the film applicator coupled with an environmental showing of a mounting part for a film applicator;

FIG. 13 is a perspective view of the first embodiment of the film applicator coupled with an environmental showing of a mounting part for a film applicator, and supporting an unclaimed cellular phone;

FIG. 14 is a perspective view of the first embodiment of the film applicator coupled with an environmental showing of a mounting part for a film applicator, and an unclaimed cellular phone and film assembly positioned within it;

FIG. 15 is a perspective view of the first embodiment of the film applicator in a closed state, wherein an environmental showing of the film extends out from the end;

FIG. 16 is a top, front, right side perspective view of the film applicator according to a second embodiment of my new design, showing a first configuration of the film applicator in an open state;

FIG. 17 is a bottom, rear, left side perspective view thereof;

FIG. 18 is a front view thereof;

FIG. 19 is a rear view thereof;

FIG. 20 is a left view thereof;

FIG. 21 is a right view thereof;

FIG. 22 is a top view thereof; and

FIG. 23 is a bottom view thereof;

FIG. 24 is a rear, top, left side perspective view the film applicator of the second embodiment, showing a second configuration of the film applicator in a closed state; and,

(Continued)

FIG. 25 is a front, top, right side perspective view of the film applicator of the second embodiment, showing a second configuration of the film applicator in a closed state; FIG. 26 is a first perspective view of the second embodiment of the film applicator coupled with an environmental showing of a mounting part for a film applicator; FIG. 27 is a second perspective view of the second embodiment of the film applicator coupled with an environmental showing of a mounting part for a film applicator; FIG. 28 is a perspective view of the second embodiment of the film applicator coupled with an environmental showing of a mounting part for a film applicator, and an unclaimed cellular phone and film assembly positioned within it; and, FIG. 29 is a perspective view of the second embodiment of the film applicator coupled with an environmental showing of a mounting part for a film applicator, and supporting an unclaimed cellular phone.

The broken lines depict portions of the film applicator in which the design is embodied that are not considered part of the claimed design.
